UNITED STATES PATENT OFFICE

136,971

DESIGN FOR A CAMERA OR SIMILAR ARTICLE

Harry G. Cunningham, Los Angeles, Calif.

Application October 29, 1943, Serial No. 111,528

Term of patent 14 years

To all whom it may concern:

Be it known that I, Harry G. Cunningham, a citizen of the United States and resident of Los Angeles, in the county of Los Angeles and State of California, have invented a new, original, and ornamental Design for a Camera or Similar Article, of which the following is a specification, reference being had to the accompanying drawings, forming a part thereof.

Referring to the drawings:

Figure 1 is a perspective view showing the front, left side and top of a camera or similar article, illustrating my new design.

Figure 2 is a side elevation showing the left side of the camera of Figure 1.

Figure 3 is a perspective view showing the front, right side and top of the camera.

Figure 4 is an elevational view of the right side of the camera.

Figure 5 is a front elevation.

Figure 6 is a rear elevation.

I claim:

The ornamental design for a camera or similar article, substantially as shown.

HARRY G. CUNNINGHAM.
